UNITED STATES PATENT OFFICE

WILLIAM W. MACLAUGHLIN, JR., OF FORT WORTH, TEXAS

DESIGN FOR AN ADVERTISING EXHIBITOR

Application filed January 24, 1931. Serial No. 38,442. Term of patent 14 years.

To all whom it may concern:

Be it known that I, WILLIAM W. MACLAUGHLIN, Jr., a citizen of the United States, residing at Fort Worth, Tarrant County, and State of Texas, have invented a new, original, and ornamental Design for Advertising exhibitor, of which the following is a specification, reference being had to the accompanying drawing, forming part thereof.

Fig. 1 is an elevational view of an exhibitor constructed in accordance with the present invention; and

Fig. 2 is a side elevational view of the same. The support in Fig. 2 is an ordinary flat easel support.

I claim:

The ornamental design for an advertising exhibitor, as shown, and described.

WILLIAM W. MACLAUGHLIN, JR.
